UNITED STATES PATENT OFFICE.

WILLIAM LUTHER BARRON, OF NEW YORK, N. Y., ASSIGNOR TO THE SINGER MANUFACTURING COMPANY, A CORPORATION OF NEW JERSEY.

THREAD CUTTING AND HOLDING DEVICE FOR SEWING-MACHINES.

1,234,258.

Specification of Letters Patent. Patented July 24, 1917.

Application filed September 6, 1913. Serial No. 788,364.

To all whom it may concern:

Be it known that I, WILLIAM L. BARRON, a citizen of the United States, residing at New York, in the county of New York and 5 State of New York, have invented certain new and useful Improvements in Thread Cutting and Holding Devices for Sewing-Machines, of which the following is a specification, reference being had therein to the 10 accompanying drawings.

My invention relates to automatic devices for two-thread sewing machines, adapted to sever the threads at the completion of a stitching operation and to nip or hold the 15 ends of the needle thread and shuttle thread during the formation of the first of a new group of stitches to insure proper interlocking of said threads. Such devices are illustrated in the patent to Gatchell, No. 798,130, 20 of August 29, 1905, and in my application for patent filed February 7, 1913; Serial No. 746,696. The object of the present invention is to improve the aforesaid devices and particularly the means for nipping the 25 shuttle thread.

In the present instance, the invention is applied to a Singer lock-stitch machine for sewing on buttons. The cutting and nipping elements include a tapered shuttle-thread blade and a tapered needle-thread blade, a shuttle thread nipping finger and a needle thread drawing hook—all carried by a carrying arm pivoted to the under side of the throat-plate of the sewing machine. 30 The carrying arm has a sector gear which meshes with a cam-actuated rack, and said cam, in conjunction with a stop-motion device, serves to impart positioning, cutting and nipping movements to the elements.

40 The needle thread drawing hook is given its initial operative movement when the machine is started to form a group of stitches. The passage of the shuttle through the needle-thread loop first presented, draws the 45 loose end of the thread down through the needle-hole; and the movement of the drawing hook serves to carry the loose thread into engagement with two members supported by the throat-plate, whereby the first 50 member, a clamping jaw, nips the needle-thread and the second member, a knife-edged notched plate, severs its loose end. A cam surface on the hook holds the spring-retracted clamping jaw against the thread 55 until two or more stitches are formed, when a second movement of the hook releases the

jaw and thus the thread. When a group of stitches is nearly completed the cam-actuated rack causes a forward movement of the carrier-arm whereby the lower thread is seized by the shuttle-thread blade, the needle-thread blade being moved close to the needle-hole. The needle descends, and, as it rises, a second movement of the carrying arm causes the seizure of the needle thread 60 loop by its blade, whereupon the final or thread-severing movement of the blades is effected, the rack and carrying arm being given a quick movement by a stop-motion lever, when the latter is operated to stop the 65 machine.

In devices of the present type the shuttle-thread when left loose at the commencement of a new group of stitches will frequently draw through one or more of the needle-thread loops. To obviate this difficulty the present invention provides simple and effective means to nip the shuttle thread before the cutting operation in such manner as to securely hold what would otherwise 70 be the loose end of the thread. The present construction renders unnecessary the employment of a cam-plate and sliding or swinging hook which form the subject of the patent to Gatchell above referred to. 75 The means employed in the present invention comprise a spring nipping-finger carried by the blade-carrying arm and so shaped and positioned with respect to the shuttle-thread blade that the movement of 80 the latter is employed to nip the shuttle-thread between the lower face of said blade and the nipping finger.

In the accompanying drawings, Figure 1 is a side view of a button sewing machine embodying the present invention. Fig. 2 is a bottom view of the same. Figs. 3 and 4 are bottom plan views of the thread-nipping and severing attachment with the parts in different positions. Fig. 5 is a perspective view of the attachment with the parts in position after the release of the needle-thread and shortly after the commencement of a stitching operation. Figs. 6 and 7 are sections of Fig. 3 at lines 6—6 and 7—7, respectively. Fig. 8 is a perspective view of the shuttle-thread blade and nipping finger showing the position of the shuttle-thread immediately prior to the severing thereof. Fig. 9 is a perspective view of the needle-thread clamp and part of the needle-throat. 110

In the present instance the invention is

applied to a Singer lock-stitch machine for sewing on buttons. As shown, the machine comprises the standard 1, overhanging arm 2 and head 3, the latter supporting a vertically reciprocating needle-bar operated from the driving shaft 4. An oscillating shuttle is fitted within the shuttle race 5 supported below the bed-plate 6, said shuttle being driven by driver 7 through oscillating shaft 8 and driving shaft 4. The driving shaft is provided with loose pulley 9 and fast pulley 10, the latter having a rigidly attached stop-motion cam 11. Pivotally mounted at its lower end in a projection 12 from the standard is a start and stop-motion lever 13 provided with a belt shifting arm 14 and with spring-pressed plunger 15. The stop-motion lever 13 is spring-pressed toward its rearward or operative position, and is detained in its forward or inoperative position by a detent-lever 16 which is maintained normally in operative engagement with the upper portion of the stop lever by means of the spring 17 in a well-known manner. The stop-lever 13 is so mounted within the projection 12 as to be capable of slight sidewise movement against the spring-pressed plunger-pin 18, shown in end view only in Fig. 1.

30 The thread-cutting and nipping elements are carried beneath the throat-plate of the machine as shown in Figs. 3, 4 and 5. - The shuttle-thread blade 19 and the needle-thread blade 20 are fixed upon swinging arm 21 carrying sector-gear 22, which gear is journaled upon a pin 23 within a bracket 24 fastened by means of screw-stud 24^x to the under side of the throat-plate 25. Rigidly secured to the arm 21 is a thread-drawing arm or hook 26 disposed adjacent the under side of the throat-plate and formed at its forward end with a barb 26'. As shown in Figs. 3, 4 and 5 the under side of the throat-plate is recessed at 27 to accommodate 45 clamping jaw 28 pivoted at 29 and normally held out of engagement with fixed jaw 30 within recess 27 by spring 31.

Meshing with sector-gear 22 is a rack 32 formed upon a lateral arm attached to sliding bar 33 supported beneath the bed of the machine and having near its rearward end a block 34 formed with a lateral notch. This notch is entered by the contracted lower end of a lever 35 pivotally mounted upon fulcrum-stud 36 carried by a bracket 37 supported by the bed-plate of the machine, said lever being provided at its upper end with a roller-stud 38 entering cam-groove 39 in the face of rotary cam-wheel 40, the latter being mounted upon the standard 1. Cam-wheel 40 is provided with a worm-wheel 41 meshing with a worm 42 fixed upon the main-shaft 4. The block 34 has a rearward extension carrying a roller-stud 43 embraced

by the forked arm of a bellcrank-lever 44 65 fulcrumed at 45 and having a second arm provided with a spring-pressed pin 46 entering a slot 47 in the lower end of stop-lever 13. The lever 35 and bellcrank-lever 44 serve, through the connections above described, to impart operative movements to the thread-cutting and nipping elements, as more fully described in patent to Horton, No. 807,676, of December 19, 1905.

In Fig. 3 the parts are shown in the position they assume when the machine is started to form a group of stitches. When the needle descends, the loose end of the needle-thread is above the work-plate, but the passage of the shuttle through the loop of 80 needle-thread draws the said loose end down through the needle-hole. As the take-up rises, cam-follower 38 travels over the inclined cam section 48 thereby moving lever 35 and its connections with sector-gear 22 to 85 impart an initial rotary movement to the latter.

The movement of sector-gear 22 will swing thread-drawing arm or hook 26 so that its hook will cross the needle-hole 50 90 thereby engaging the loose end of the needle-thread and drawing the latter to one side as shown in Fig. 7 and between the nipping jaws 28 and 30. When the thread is so placed, a cam surface 26'' formed on the thread-drawing arm or hook will engage pin 28' carried by clamping jaw 28, closing said jaw against the stress of its spring to grip and hold the thread. The continued movement of arm 26 will carry the thread into engagement with notched plate 52 to effect the cutting of the thread between the knife edge of said plate and barb 26', as indicated in Figs. 4 and 7. The cam-follower then passes on to the dwell 49 of the cam-wheel. The hook 26 maintains its position (Fig. 4) to hold the clamp closed until two or more stitches are formed, whereupon follower 32 leaves the dwell of the cam and reaches the inclined section 51 of the cam groove. At this point the hook is given a second movement which carries the parts to the position shown in Fig. 5, the needle-thread being released by the retraction of clamp-jaw 28.

The parts are held in the position shown in Fig. 5 by dwell 52 in the cam until the close of a stitching operation, when the follower leaves dwell 52 and reaches an inclined section of the cam-groove. At this point the carrying arm and blades 19 and 20 will be advanced sufficiently to enable blade 19 to engage the shuttle-thread. The blades will then have a short period of rest while the follower is on a short dwell and will then move so that, on the next descent of the needle, blade 20 will engage the needle-thread loop, and the two threads will be

severed by the overthrow of the stop-lever at a point when follower 38 reaches a dwell section in the cam. That is to say, the blades 19 and 20 will be given a quick movement 5 to their extreme forward position to sever the thread and will then be restored to the initial position shown in Fig. 3, as fully described in the patent to Horton above referred to.

10 A description will now be given of the means for nipping the lower or shuttle thread to which the present invention more particularly relates, the foregoing description of the elements used in connection with 15 said nipping means being necessary to a complete understanding of the invention.

Mounted upon carrying arm 21 and fastened thereto by means of screw 57 and pin 58 is the shank 59 of a spring nipping finger 20 60 which is held against the lower face of shuttle-thread blade 19 and which, at its outer end, is depressed and offset from the edge of said blade. When the shuttle thread is seized by blade 19 in the movement of the 25 parts from the position shown in Fig. 5 to the position shown in Fig. 4, said thread is drawn over the tapering point of the blade until that portion leading to the shuttle passes between the blade and the offset 30 point of spring nipping-finger 60.

The succeeding movement of blade 19 to cutting position, as shown in Figs. 3 and 6, is utilized to draw the shuttle thread between the lower face of the blade and the upper 35 spring-pressed face of the nipping finger. The thread leading from the shuttle is held firmly between the finger and the blade when the parts are given a quick forward cutting movement by the overthrow of the stop-lever, as previously described, and likewise during a corresponding return movement of the parts to the initial position shown in 40 Fig. 3. The shuttle-thread is held by the nipping elements during the movement of 45 the parts to the position shown in Fig. 4, which effects the nipping of the needle-thread and the severing of its loose end, and until several stitches of a new group are formed, the feeding of the work above the 50 throat-plate serving to withdraw the shuttle thread from the nipping finger, as will be understood without further explanation.

Having thus set forth the nature of the invention, what I claim herein is:—

55 1. In a sewing machine, the combination with stitch-forming devices, of a movable thread-cutter for severing the thread, and means for nipping the thread before a thread cutting operation comprising a nip-

ping finger carried by and coöoperating with 60 said thread-cutter in nipping the thread between itself and the adjacent face of the thread-cutter.

2. In a sewing machine, the combination with stitch-forming devices and a movable 65 thread-cutter for severing the thread, of means for nipping the thread before a thread cutting operation comprising a spring nipping finger moving with said thread-cutter and pressed toward one face thereof against 70 which it is adapted to grip the thread.

3. In a sewing machine, the combination with stitch-forming devices of a movable thread-cutter for severing the thread, a 75 spring nipping finger sustained in fixed position relatively to said thread-cutter, and means including said thread-cutter for guiding the thread between its face and the nipping finger before the thread cutting operation.

4. In a sewing machine, the combination with stitch-forming devices and a movable thread-cutter for severing the thread, of a swinging support for said thread-cutter, and a nipping finger carried by said swinging 85 support and spring-pressed against one face of said thread-cutter, the outer end of said finger being bent from the face of the thread-cutter and offset to form a thread-guide.

5. In a lock-stitch sewing machine having a needle and a shuttle and making a predetermined number of stitches, means for nipping and trimming the beginning end of the needle-thread at the start of the cycle of 95 operations, means for cutting the finishing ends of the needle- and shuttle-threads, and means for nipping the shuttle-thread toward the end of a cycle of operations, said last-named means being movable with the means 100 for cutting a finishing end of thread.

6. In a lock-stitch sewing machine having a needle and a shuttle and making a predetermined number of stitches, means for cutting the finishing ends of the needle- and 105 shuttle-threads, and means for nipping the shuttle-thread toward the end of a cycle of operations, said last-named means being movable with the means for cutting a finishing end of thread.

In testimony whereof, I have signed my name to this specification, in the presence of two subscribing witnesses.

WILLIAM LUTHER BARRON.
